DEVICE FOR WINDING AND CUTTING CELLOPHANE

Louis G. Stanciff, Cincinnati, Ohio

Application July 28, 1936, Serial No. 93,044

9 Claims. (Cl. 242—56)

The present invention relates to a means for winding and cutting material which is packaged in roll form to obtain sheets of the material; the means being particularly applicable for use in connection with "Cellophane" webs.

Heretofore various devices have been employed for cutting "Cellophane" but they have generally been of a complicated mechanism and therefore prohibitive to the consumer of small quantities of the material.

An object of the invention therefore is to provide a simplified device for cutting sheets of "Cellophane" from rolls of the material which is within the means of the small consumer thereof.

Another object of the invention is to provide a novel means of cutting the "Cellophane" which is positioned upon the winding reel proper.

A further object of the invention is to provide a device which is quickly assembled for operation and which occupies a small space when not in use.

Other objects will become apparent from the following specification and drawing, in which:

Fig. 1 is a front elevational view of the device of my invention.

Fig. 2 is an enlarged view taken on line 2—2 of Fig. 1, only part thereof being shown in cross section.

Fig. 3 is a cross sectional view taken on line 3—3 of Fig. 2.

Fig. 4 is a perspective view of the cutter means of my invention similar to the form shown in Fig. 2.

Fig. 5 is a cross sectional view taken on line 5—5 of Fig. 2.

Fig. 6 is a cross sectional view of a modified form of cutter means.

The preferred embodiment of my invention consists of a roll of "Cellophane" 8 or similar material, wound on a core 9 which is rotatably mounted on a horizontally extended axis 10. The axis is positioned on any convenient supporting base 11, such as a vertical wall by means of a plate 12 integral with the axis and fastened to the wall by bolts 13.

A web 14 of "Cellophane" which is to be cut into sheets is taken from the roll by a winding reel (generally indicated as 15) which comprises a rotatable frame 16 having two adjustable arms 17 and 18 intermediate the ends thereof. The frame is mounted on a centrally disposed axis 19 which is in the form of a threaded lug extending outwardly from a bracket 20 and which is fastened to the wall 11 by means of screws 21.

The frame is also provided with longitudinal slots 22 and 23 which extend radially from the axis thereof to position the arms in adjustable spaced relationship thereon. The arms 17 and 18 are mounted in the slots of the frame by means of integral shoulders 24 and 24' and threaded portions 25 and 25' respectively, the latter being adapted to receive wing bolts 26. To preclude rotation of the arms whilst the reel is in operation or when the bolts are tightened to the frame 10 the arms are furnished with square portions 27 and 27' respectively (Fig. 5) which extend from the abutting surface of the shoulders 24 and 24' and partially into the slots 22 and 23.

The "Cellophane" cutting means for the device 15 is incorporated in the arm 17 which is preferably made of hollow tubing. A rod 28 is held in the arm (Fig. 3) and is of smaller dimensions than the hollow portion of the arm to allow horizontal movement of the rod therein. The rod is furnished with a vertical slot 29 at its inner end which encloses the lower end of a knife 30, a countersunk screw 31 being provided to fasten the knife to the rod. A longitudinal slot 32 formed in the uppermost portion of the arm 17 25 provides an opening or way from which the knife projects and also functions as a guide in which the knife may move to determine its limits of motion. In order to obtain an efficient cutting action, the plane of the knife edge 33 is positioned 30 at an obtuse angle relative to the plane of the work. To provide a simple means of assembling the rod and the knife in the arm 17 a circular bore 34 is made in the tube which is adjacent the position of the parts and in line with the 35 counter-sunk screw 30.

An extension 35 of the rod beyond the free end of the arm 17 furnishes a handle whereby the reel may be rotated to wind the "Cellophane" thereon and also provides a means of pulling the 40 knife outwardly through the "Cellophane" to sever it into desired sheets. As indicated in Fig. 3 the shoulder portions 24 of the arms 17 and 18 are provided with a small indicator point 36 which in conjunction with the calibrations 37 45 made along the edge of the frame 16 determines the exact positions at which the arms are to be adjusted to obtain any desired length of sheet from the "Cellophane" web.

A modified form of cutting means is shown in 50 Fig. 6. There the arm 17 has a longitudinal slot 32 for guiding the knife 38. The rod 39 enclosed in the tubing has much smaller dimensions than the hollowed portion of the arm to allow vertical movement of the rod in the tube. The knife 1

38 is formed by tapering the inner end of the rod, bending it upwardly and then grinding it to an edge 40. A spring 41 is fastened to the rod, subjacent the knife portion, to urge the knife upwardly in cutting position. If for any reason the knife is unable to cut through the work, the inclination of the knife will depress the spring. By releasing the outward pressure on the rod, it is obvious the spring will return the rod to its normal cutting position. This action creates a sawing motion of the knife on the work which permits the knife to cut through the obstacle encountered. It is contemplated that this arrangement may be used in conjunction with the form of knife illustrated in Figs. 2, 3, and 4.

In operation the material from the roll 3 is secured in any suitable manner to the arm 17 of the winding reel and the extension or handle 35 thereof is then grasped and rotated, (Fig. 1). When the desired length of web material has been wound on the reel the same handle or extension 35 is pulled outwardly to bring the knife through the material to cut said web into sheets. By adjusting the arms to the indicated calibrations any desired length of sheet may be easily obtained.

It is to be understood that my device is not limited to its use for "Cellophane" and may be used with other forms of web material from which sheets are to be cut.

What I claim is:

1. In a device for winding and cutting web material, the combination of, a rotatable winding reel comprising a plurality of arms held in spaced relationship thereon, a cutting knife, and means for mounting the knife for longitudinal movement on one of the arms and with its cutting edge projecting beyond the surface of the arm.
2. In a device for winding and cutting web material, the combination of, a rotatable winding reel comprising a plurality of arms held in spaced relationship thereon, a cutting knife, means for mounting the cutting knife on one of the arms with its cutting edge projecting beyond the surface of the arm, and means for moving the knife in the direction of extension of the arm to sever the material wound on the reel.
3. In a device for winding and cutting web material, the combination of, a rotatable winding reel comprising a plurality of arms held in spaced relationship thereon and each arm having a surface for engaging and holding the material wound on the reel, means for mounting a cutting knife on one arm with its cutting edge projecting from said surface, and means for moving the knife in the direction of extension of the arm and in parallelism therewith to sever the material wound on the reel.
4. In a device for winding and cutting web

material, the combination of, a rotatable winding reel comprising a plurality of arms held in spaced relationship thereon, one arm having a slot therein, means for mounting a cutting knife on the arm with its cutting edge projecting from the slot, and means for moving the knife in the direction of extension of the arm and in parallelism therewith to sever the material wound on the reel arms.

5. In a device for winding and cutting web material, the combination of, a rotatable winding reel comprising a pair of arms held in adjustable spaced relationship on opposite sides of the reel axis, one arm provided with a slot, and a cutting knife projecting from the slot and adapted to sever the material wound on the reel upon movement of said knife longitudinally of the arm.

6. In a device for winding and cutting web material, the combination of, a rotatable winding reel comprising a pair of arms held in adjustable spaced relationship on opposite sides of the reel axis, one arm provided with a slot, and a resilient cutting knife projecting from the slot and adapted to sever the material wound on the reel upon movement of said knife longitudinally of the arm.

7. In a device for winding and cutting web material, the combination of, a rotatable winding reel, a pair of tubular arms held in adjustable spaced relationship on opposite sides of the reel axis, a movable rod held in one arm and extending therefrom, said arm provided with a slot, and a cutting knife fastened to the rod and projecting from the slot, the rod being adapted to move the knife longitudinally of the arm to sever the material wound on the reel.

8. In a device for winding and cutting web material, the combination of, a rotatable winding reel, a pair of tubular arms held in adjustable spaced relationship on opposite sides of the reel axis, one arm provided with a slot, a movable rod held in said arm and extending therefrom, a cutting knife fastened to the rod and projecting from the slot, and a spring mounted beneath the rod subjacent the cutting knife, the rod being adapted to move the knife longitudinally of the arm to sever the material wound on the reel.

9. In a device for winding and cutting web material, the combination of, a rotatable winding reel, a pair of tubular arms held in adjustable spaced relationship on opposite sides of the reel axis, means for precluding independent rotation of the arm, one arm provided with a slot, a movable rod held in said arm and extending therefrom, and a cutting knife fastened to the rod and projecting from the slot, the rod being adapted to move the knife longitudinally of the arm to sever the material wound on the reel.

LOUIS G. STANCLIFF. 60
